US0D1105181S

(12) **United States Design Patent** (10) Patent No.: **US D1,105,181 S**
(45) Date of Patent: ** Dec. 9, 2025

(54) **DEBRIS CONTAINER**

(71) Applicant: **iRobot Corporation**, Bedford, MA (US)

(72) Inventors: **Jason Jeffrey Suchman**, Arlington, MA (US); **Douglas Dell'Accio**, Boston, MA (US); **Andrew Vincent Wolff**, Norfolk, MA (US); **Flavia Pastore**, Wakefield, MA (US)

(73) Assignee: **iRobot Corporation**, Bedford, MA (US)

(**) Term: **15 Years**

(21) Appl. No.: **29/996,247**

(22) Filed: **Mar. 31, 2025**

CLAIM

The ornamental design for a debris container substantially as shown and described.

DESCRIPTION

FIG. 1 is a perspective view of the debris container.

FIG. 2 is a front view thereof.

FIG. 3 is a back view thereof.

FIG. 4 is right side view thereof.

FIG. 5 is left side view thereof.

FIG. 6 is top view thereof; and,

FIG. 7 is bottom view thereof.

The broken lines illustrate environmental features that form no part of the claimed design.
